DISK PERFORATOR FOR PIPES IN WELLS

James Luther Johnston, Longview, Tex., assignor
of one-half to Edgar C. Johnston, Longview,
Tex.

Application April 13, 1946, Serial No. 661,939

11 Claims. (Cl. 164—0.3)

1

The invention relates to a closure perforator for pipe. Under various sets of conditions, it is often necessary to provide a frangible or perforatable closure in a pipe so as to prevent the flow of fluid therethrough until a predetermined time. In order to perforate or break such a closure, an assembly is provided which can be moved in the pipe so as to strike the closure, causing it to be broken or perforated.

After the perforation or breaking of the closure, it is desirable to then remove all of such perforator members from the pipe so as to permit full flow of fluid therethrough, and the present invention contemplates the provision of such an arrangement.

It is one of the objects of the invention to provide a perforator of closures in pipe whereby both the closure and perforator can be removed from perforating position by the flow of fluid after the perforation.

Another object of the invention is to provide a perforator for closures in pipe which substantially fills the pipe so that the flow of fluid along the pipe, after the perforation will remove the plunger so as to leave the pipe open for a full flow of fluid.

Another object of the invention is to temporarily lock a pipe perforator in position in the pipe so that it can be released by the reaction of the perforating movement to thereafter flow with the fluid in the pipe.

Another object of the invention is to provide a perforator for closures in pipe which has a sealing means there-around so as to be forced along with the flow of fluid released by the perforations.

Other and further objects of the invention will be readily apparent when the following description is considered in connection with the accompanying drawings, wherein:

Fig. 1 is a vertical sectional view illustrating the assembly in a pipe in a well where the plunger is temporarily locked in position.

Fig. 2 shows a modified arrangement of the plunger just about ready for movement to perforate the closure.

Fig. 3 shows still another form of the invention with the plunger adjacent the closure and ready to perform the perforating operation.

In Fig. 1 a string of pipe 2 is shown. Pipe of this sort is usually located in a well bore and may be in the form of casing, tubing, a formation testing string of pipe, or any other pipe which it is desired to maintain closed until a predetermined time. The pipe is made up of an upper

section 3 and a lower section 4. The upper section is provided with the internal passage 5 and the lower section has a passage 6 which is here shown in Fig. 1 as somewhat reduced in diameter as compared with the passage 5.

The upper end of the pipe 4 has a threaded box member 7 so that a shoulder 8 supports a closure 9 which may be a frangible or perforatable disc or plate of any desired type. Fig. 1 is a section to illustrate glass or similar material, however, it is intended that a thin metal disc or a disc of frangible metal or other suitable composition may be employed. This closure is held in position by the pin member 10 on the lower end of the upper pipe section 3. This pin has the reduced passage 11 which in turn forms a shoulder 12. This shoulder is arranged to support the lower end of a coil spring 14 which in turn supports a plunger 15. This plunger has the pointed lower end 16 which is adapted to engage the closure 9 to perforate or break the closure. This plunger is made up of the body 17 of which the end 16 is a part. The plunger is enlarged at 19 so as to form a shoulder 20 which rests on the upper end of the spring 14.

The upper end 23 of the plunger may be formed in any desired manner so that it may be gripped by a fishing tool if desired, but particularly so as to present an upper surface 24 which is arranged to be struck by an object dropped down through the pipe 2. Fig. 2 shows such an object 25 in the form of a weight having the guide springs 27 on the sides thereof. It is intended of course that any pipe nipple or object may be used. The function of this object is to strike the plunger 15 and to cause it to move down sharply so as to perforate or break the closure 9.

It is desirable that the plunger be temporarily locked in the pipe so that it will not be moved out of striking position and to accomplish this the interior of the pipe is formed with an annular recess 30, which receives the balls 31 carried in the openings 32 in a collar 33. The balls, the recess 30, and the plunger 15 are of such relative sizes that the plunger will fit snugly through the opening 34 in the collar and retain the balls in the recess 30. This locks all of the parts together. The plunger has a conduit 35 therethrough which is divided and has the lateral discharge ports 36 therethrough. In this manner there may be a circulation of fluid down through the plunger.

It will be noted that the plunger and the collar 33 substantially fill the passage 5 in the pipe.

With the parts shown in the position of Fig. 1,

a weight or other object can be dropped downwardly in the pipe 2 which may or may not be filled with liquid. The usual purpose of the closure 9 is to prevent the entrance of any fluid into the pipe 2 until such time as the pipe is properly located and the closure broken.

When the object falling through the pipe strikes the upper end 24 of the plunger, the plunger will move sharply downwardly so as to rupture the closure 9. This downward movement compresses the spring 14 so that as soon as the inertia of the parts is stopped, there will be a reaction of the spring, tending to throw the plunger upwardly. The collar 33, however, remains in locked position by the balls 31. It is intended that the reaction of the spring 14 will throw the plunger upwardly sufficiently to remove the point from the punctured closure. When the plunger is to be removed, a suitable fishing tool can be lowered into the well bore to grip the tapered head 23 so as to exert a pull thereon and to raise the plunger to bring the reduced portion 37 up to the elevation of the balls 31. This permits the balls to move inwardly out of the recess 30 and release the assembly from the latched position. This upward movement in the plunger allows a full flow of fluid through the passage 6. The movement of the plunger assembly permits the fluid to move up in the well and of course if the fluid flow is sufficient it may be elevated to the surface.

In Fig. 2 a plunger 40 is shown as having the pointed lower end 41 and having the closed internal cavity 42 to reduce the weight thereof. This plunger has the swab cups 43 thereon which are made up of the frusto-conical resilient cups 44 retained in position by the springs 45 which are in turn confined at the lower end by a ring 46. Two of these swab cups are shown.

The closure 50 is supported between the lower end of the upper pipe section 51 and the upper end of the lower pipe section 52 where the pipe sections are connected by a coupling or collar 53. This closure may be of any type as illustrated as being of material such as cast iron.

The upper end of the plunger has a head 55 thereon which is arranged to be struck by the weight or object 25.

This plunger 40 may be positioned as shown in Fig. 2 when the pipe is lowered into the well, then the weight 25 drops so as to break the closure 50 and the flow of fluid then moving upwardly in the pipe will exert a pressure under the swab cups so as to force the plunger out of the broken closure and upwardly in the pipe.

Fig. 3 shows a plunger body 60 which is similar to that described in Fig. 2 except that a plunger rod 61 is slidable therein and has the perforating head 62 on the lower end. A coil spring 63 is disposed between the body 60 and the retainer ring 64 is threaded on the upper end of the rod 61. The swab cups fit sufficiently tight inside of the pipe 66 to retain the parts in the position shown.

When the object 25 strikes the upper end 67 of the rod 61, it will be snapped downwardly to break the closure 50. The spring 53, however, absorbs the impact of the weight so that the backing cups will not be sheared from the cylindrical body 60.

Broadly the invention contemplates a closure perforator for pipes wherein the fluid flow which is initiated by the breaking of the closure will remove the perforating assembly from within the closure and force it along the pipe.

What is claimed is:

1. A disc perforator assembly for well pipe comprising a pipe connection, a frangible flat disc seal retained thereby, means movable in the pipe to engage and break said disc including a plunger, means to normally latch said plunger in the pipe above said disc, additional means movable in the pipe to strike and release said plunger to break said disc, and still additional means on said plunger to allow retraction to be effected from the broken disc.

2. A disc perforator for wells comprising a body, a lower end on said body to engage and break a frangible disc in the well pipe, and means 15 also on said body to be engaged by fluid moving up in the well after the disc is broken so as to move said end out of the broken disc.

3. A perforator for pipe obstructions comprising a body, a member thereon to engage and break the obstruction, and means on the body to substantially fill the pipe around the said member so that the flow of fluid released by such break will thereafter remove said member from the break to be carried along the pipe with the 20 flow of fluid.

4. A pipe in a well, a frangible closure for said pipe, a plunger to engage and perforate said closure, an enlargement about and above said plunger to substantially fill the pipe so that the flow 30 of fluid upwardly in the pipe through the perforated closure after the perforation will move said plunger out of the perforated closure.

5. A pipe in a well, a frangible closure for said pipe, a plunger to engage and perforate said 35 closure, an enlargement on said plunger to substantially fill the pipe this characteristic causing the flow of fluid in the pipe after the perforation to move said plunger out of the perforated closure, said enlargement comprising a 40 collar about the plunger.

6. A pipe in a well, a frangible closure for said pipe, a plunger to engage and perforate said closure, an enlargement on said plunger to substantially fill the pipe, said enlargement comprising a 45 collar about the plunger, and means in said collar and engaged by said plunger to lock the collar in the pipe.

7. A pipe in a well, a frangible closure for said pipe, a plunger to engage and perforate said 50 closure, an enlargement on said plunger to substantially fill the pipe, said enlargement comprising a collar about the plunger, and means in said collar and engaged by said plunger to lock the collar in the pipe, said means being releasable by 55 upward movement of the plunger after the perforation.

8. A pipe in a well, a frangible closure for said pipe, a plunger to engage and perforate said closure, an enlargement on said plunger to substantially fill the pipe so that the flow of fluid in the pipe after the perforation will move said plunger out of the perforated closure, said means including a resilient sealing member carried by 60 the plunger.

9. A pipe in a well, a frangible closure for said pipe, a plunger to engage and perforate said closure, an enlargement on said plunger to substantially fill the pipe this characteristic causing the flow of fluid in the pipe after the perforation to move said plunger out of the perforated closure in movable position thereon.

10. A pipe in a well, a frangible closure for said pipe, a plunger to engage and perforate said closure, an enlargement on said plunger to sub-

stantially fill the pipe this characteristic causing the flow of fluid in the pipe after the perforation to move said plunger out of the perforated closure in movable position thereon, and a spring between said plunger and sealing means to absorb the shock of movement of the plunger.

11. A perforator for a closure in a pipe in a well comprising a collar in the pipe, a recess in the interior of the pipe, lock balls in the collar and fitting into said recess, a plunger in the collar and engaging said balls to hold them in locking position, a spring in the pipe supporting said plunger, a frangible closure adjacent said plunger, said plunger being movable downwardly when struck from above to perforate said closure, compress said spring and then be thrown upwardly

by the spring to be released from the closure, and means on said plunger to be engaged so as to elevate said plunger to release said balls and collar to permit movement of the plunger and collar upwardly.
